[57] ABSTRACT

A method for lifting and moving massive loads using ground-supported-clinching chassis means equipped with pressurized air to perform the lifting and lowering operations at the opposite ends of the moving operation and to cushion the load and protect the same against harmful torsional strains. The apparatus chassis utilizes separate chassis sections hingedly connected together crosswise of the path of travel and provided with jaws for gripping the load from its opposite sides and activated by the inflation of the chassis air spring. The load clinching vehicle can be used to move various loads including massive reinforced concrete girders or the like either alone or while used to support lading, as a building, machinery, etc. Similar chassis units are located at either end of each girder to be moved and equipped with steerable fifth wheel dolly units.

METHOD FOR MOVING MASSIVE LOADS

This application is a division of my copending application Ser. No. 4,928, filed Jan. 22, 1970, now abandoned, entitled Method and Apparatus for Moving Massive Loads.

The movement of very heavy loads over uneven ground surfaces without imparting serious strains to the load presents serious problems not satisfactorily resolved by transporting equipment heretofore available. For example, let it be assumed that it is desired to move a frame or other type of building or a girder such as a precast reinforced concrete girder from one location to another over the ground. Loads of this type must be loaded onto the moving vehicle while the load is supported at a minimum height above a foundation or other support. Heretofore heavy raising and lowering equipment and auxiliaries have been necessary to transfer the load onto the transport vehicles as well as to remove it from such vehicles after reaching a destination. Furthermore, serious problems have been presented in protecting the load against shock, high pressure points, and miscellaneous strain and torsion forces during transit.

By the techniques and expedients exemplified in the present invention it is feasible to move very large loads over relatively rough terrain in remote and isolated regions not accessible to modern-day heavy equipment except by costly aerial transport. The invention equipment makes it possible and feasible to construct massive assemblies such as precast girders and other structural units at a convenient assembly point and then transport them to an installation site using simple, lightweight, highly effective transport equipment readily flown into the area.

The invention transport equipment typically comprises a pair of specially constructed load clinching vehicles designed for endwise movement beneath the opposite ends of the load while the vehicle frame is lowered by deflating its air bellows suspension units. Once the vehicles are in place the air bellows are inflated, as from an air supply carried on the vehicles, thereby elevating the vehicle frames upwardly against the underside of the load while simultaneously activating jaws effective to clench the load therebetween. The specially constructed transport vehicles are made in two halves hinged together longitudinally of the vehicle with the sections disposed to either side of the load cooperating to grip the load therebetween. The vehicle chassis is supported on pneumatic tires and the pressurized air bellows employed to activate the clinching jaws are located between these jaws and the supporting wheels and are pressurized sufficiently to provide a desired degree of soft resilient support for the particular load then being carried. In consequence, uneven ground, jars, jolts and torsional forces likely to be encountered during transit are effectively cushioned and isolated from the load proper. If a building, heavy machinery or the like is to be moved, suitable rigid girders are installed beneath the load on supports having sufficient ground clearance to permit the bottom portion of the U-shaped frame forming part of the transport vehicle chassis to be moved into position beneath the girder ends. Thereafter the deflated air bellows are inflated to elevate the girders and the load thereon while closing the clamping jaws against the girder walls. The steerable wheels of the transport vehicle are then connected to the hauling tractors and moved to a new site.

It is therefore a primary object of the invention to provide a novel method and transport vehicle for use in moving massive loads from one location to another while supporting the load proper on multiple air cushions.

Another object of the invention is the provision of a novel method of moving a heavy load using a load clinching vehicle formed in two sections movably connected together so as to grip a load from its opposite lateral sides.

Another object of the invention is the provision of a method of moving a heavy load using separate chassis sections equipped with inflatable air springs and hinged together between their opposite sides with the portions on either side straddling the underside of the load and movable toward one another to grip the load as its weight is assumed by the vehicle.

Another object of the invention is the provision of a unique method of moving a heavy load sensitive to torsional strains using a pair of transport vehicles each comprising a pair of halves hinged together lengthwise of their lower portions so as to straddle a load from its underside and equipped with vertically extendable air cushions operable as they are pressurized to pivot toward one another to lift the load from its support without harmful torsional strains.

These and other more specific objects will appear upon reading the following specification and claims and upon considering in connection therewith the attached drawing to which they relate.

Referring now to the drawing in which a preferred embodiment of the invention is illustrated:

FIG. 1 is a side elevational view showing one illustrative mode of using the invention transport vehicle to move a heavy load supported on an underlying girder;

FIG. 2 is a side elevational view on an enlarged scale of one of the invention transport vehicles;

FIG. 3 is a transverse sectional view on an enlarged scale taken along line 3—3 on FIG. 2;

FIG. 4 is a sectional view similar to FIG. 3 but showing the vehicle air cushions in expanded condition to support the load firmly clenched between the jaws thereof;

FIG. 5 is a fragmentary top plan view taken along line 5—5 on FIG. 2 and showing primarily only one section of the vehicle chassis.

Referring initially and more particularly to FIGS. 1 and 2, there is shown an illustrative embodiment of a pair of the invention load clinching vehicles, designated generally 10, supporting the opposite ends of a rigid girder 11 and underlying a heavy object 12 ready for movement to a new location. Also shown in FIG. 1 is a separate tractor or truck such as the pulling truck 13 and the pushing truck 14 each suitably coupled to the steering draft tongue 15 of vehicle 10.

As best appears from FIGS. 3 and 4, vehicle 10 comprises a pair of similar chassis sections 18, 18' which differ from one another only in that one is designed for use on the right hand side and the other on the left hand side of the path of travel. Since otherwise the two chassis sections are identical only one section need be described in detail. Each chassis section includes a rigid main frame 19 suitably constructed from structural steel members welded together. The rear end of main frame 19 is supported by a pneumatically tired wheel 20 journalled to an axle 21 and having its opposite ends rigidly secured by clamping means 22 to a spring beam

23. The forward end of this spring beam serves additionally as a draft transmitting member movably connected by pivot pin 24 to a hanger bracket 25 welded to main frame 19. The rear ends of spring beams 23 project rearwardly of axle 21 and support a pair of heavy duty expandable air bellows 26,26 having their upper ends underlying and secured to main frame 19.

The forward end of main frame 19 is supported on a fifth wheel dolly unit 30 having a rigid frame 31 underlying the forward end of frame 19 and secured thereto through a fifth wheel 32 of suitable construction having a vertical pivot axis substantially overlying the dolly axle. The dolly frame 31 is connected to a pneumatically tired wheel 34 similarly to rear wheel 20, namely, by a spring beam 35 and an air bellows spring 36. Wheel 34 is journaled to an axle 37 having its opposite ends connected to the overlying spring beam by a coupling 38.

Chassis sections 19,19' are movably coupled to one another in the manner clearly illustrated in FIGS. 2-5. As there illustrated by way of example, the coupling means comprises a pair of powerful hinge leaves 40,40' hinged together by a hinge pin 41 extending lengthwise of the vehicle and located close to the ground between wheels 20,34. The hinge leaves comprise suitable structural steel members flaring upwardly and outwardly into rigid welded connections with the frames of the respective chassis sections. The location of the hinge leaves between the front and rear wheels 34,20 distributes the load forces equitably between the opposite ends of main frame 19 and to each of the vehicle wheels.

The powerful clamping jaws 43,43' characterizing the invention vehicle have their clamping surfaces lying in parallel vertical planes and positioned to grip the opposite outer lateral faces of a load, such as the web portion 45 of the girder 11 (FIGS. 3, 4). Jaws 43,43' are secured to the hinge leaves 40,40' by suitable connector members such as struts 46 and the horizontally disposed stringer members 47.

Pressurized air for use in inflating the air bellows or cushions 26,36 is preferably stored in air tanks 50 mounted along either side of the chassis frame and rechargeable with air from a compressor from time to time as the supply needs replenishment. Each tank is connected with an adjacent one of the air bellows 26 or 36 by an air hose 51 under the control of a manually operable valve, not shown. Also the operatively associated pairs of air bellows are cross connected by a flexible hose 52 having multiple functions. For example, this connection permits inflating the air cushions from either supply tank. Additionally, cross connection 52 performs the important functions of equalizing the pressure between a pair of the bellows to accommodate irregularities in the ground surface traversed by the vehicle and permits the chassis sections to tilt toward and away from one another.

The operation of the described load clinching vehicle will be readily understood from the foregoing description of its principal sub-assemblies and their operative relationship to one another. When vehicles 10 are not in use a screw jack or the like extending crosswise between the forward ends of main frames 19,19' may be employed to hold the clamping jaws 43,43' stabilized in a desired open position wide enough to receive the web of a girder 11. It will of course be evident from FIGS. 3 and 4 that the carriage sections 18,18' are

slightly counterbalanced to pivot toward one another about the hinge pivot 41. Accordingly, the referred-to screw jack is desirably located between the forward ends of the main frames 19,19' to hold these frames spaced apart. While so positioned and with all air bellows 26,36 deflated to positions shown in FIGS. 2 and 3, vehicles 10 are maneuvered until their respective jaw members are properly positioned astride the opposite ends of girder 11. During this operation girder 11 is supported on spacer blocks 55 (FIG. 2) with its lower edge above the ground. Under these conditions the portion of the hinge leaves immediately to either side of hinge pin 41 underlie the lower edge of the girder and do not interfere with maneuvering the vehicles lengthwise of the girder end.

Once the vehicles are in proper position to engage the girder, control valves for air storage tanks 50 are opened admitting pressurized air into the spring bellows 26,36. As these expand they cooperate in raising the vehicle frame upwardly carrying with it hinge leaves 40,40'. The removal of the jack between the outer ends of frame 19 as inflation starts permits the chassis sections to pivot toward one another until jaws 43,43' engage the web of the girder. Further release of pressurized air into the air bellows forces the jaws into high pressure clamping action against web 45 thereby picking up the girder and lifting it out of contact with blocks 55. When the load is in its elevated carrying position the air springs are in the expanded condition shown in FIG. 4 and tractors or trucks 13,14 can be used to move the girder and any load supported thereby to a new location.

While the load is in transit it will be recognized that it is supported on a multiplicity of air cushions 26,36 and additionally by the pneumatic tires 20,34. The principal cushioning effect is provided by the air bellows since the pressure in the latter is readily controlled by the inflating control valves to that pressure providing a soft ride for the particular load being transported. Any irregularities encountered in the path of any wheel are readily compensated for by the air cushions and the cross connections 52 between associated pairs of cushions. In consequence the load can be moved with safety and without risk of introducing torsional strains to which many structures are so sensitive. Furthermore, the air cushions serving to maintain the clinching jaws 43,43' in closed position are resiliently biased into contact with the load by the cushioning action of the air springs.

Upon arrival at the destination, the load is readily detached from the vehicles without need for auxiliary equipment of any kind. Thus it is merely necessary to place either permanent or temporary supports beneath the underside of the girders. Thereafter it suffices to release air from the air spring 26,36 by venting valve means of any well known form thereby allowing the vehicle frames to settle until the load is in contact with the underlying supports. Continued deflation of the air springs lowers the vehicle completely out of contact with the girders. Thereupon, vehicles 10,10 may be withdrawn from the opposite ends of the girders and moved into position to pick up a new load in the manner already described.

While the particular method for moving massive loads herein shown and disclosed in detail is fully capable of attaining the objects and providing the advantages hereinbefore stated, it is to be understood that it

is merely illustrative of the presently preferred embodiment of the invention, and that no limitations are intended to the details of construction or design herein shown other than as defined in the appended claims.

I claim:

1. That method of moving a long massive load sensitive to torsional strains over an irregular surface which comprises: introducing astride the opposite ends of the load to be moved a pair of pneumatically tired chassis units each equipped with load supporting frames mounted on inflatable air pillow suspension means located adjacent either lateral side of each end of said chassis units, inflating said air pillow suspension means at each end of the load gradually thereby elevating the load clear of the former support therefor, maintaining said air pillow suspension means sufficiently inflated to provide a soft cushion support for the particular load being moved, utilizing said inflated pillow suspension means to minimize torsion stresses along the length of said massive load, and applying a draft force to the chassis unit at the leading end of said load adequate to move the load to its destination as said air pillow suspension means isolate the load from ground irregularities, shock forces and torsional strains.

2. That method defined in claim 1 characterized in the step of using chassis units equipped with load supporting frames having portions thereof hinged to one another along axes extending lengthwise of the load to be transported.

3. That method defined in claim 1 characterized in the step of inflating said air pillow suspension means from a supply of pressurized air stored on said chassis units.

4. That method defined in claim 2 characterized in the step of utilizing chassis units having a single row of pneumatically tired wheels along either side of the load being moved.

5. That method of moving a long heavy concrete beam or the like along the ground while protecting the same against shock, torsional strains and irregularities in the ground surface which comprises, inserting a chassis unit equipped with pneumatically tired wheels and a multiplicity of air pillows beneath and astride the

opposite ends of the beam while said air pillows are deflated and which air pillows are located along either side of each chassis unit, gradually inflating said air pillows sufficiently to lift said beam and support all portions thereof clear of the ground over which the beam is to be moved while providing a soft resilient support for said beam and minimizing torsional stresses lengthwise of the beam or the like being transported, and applying propelling forces to said chassis to move said beam to a new location as said multiplicity of air pillows cooperate in absorbing shocks, ground irregularities and roadway conditions tending to set up torsional strains lengthwise of said beam.

opposite ends of the beam while said air pillows are deflated and which air pillows are located along either side of each chassis unit, gradually inflating said air pillows sufficiently to lift said beam and support all portions thereof clear of the ground over which the beam is to be moved while providing a soft resilient support for said beam and minimizing torsional stresses lengthwise of the beam or the like being transported, and applying propelling forces to said chassis to move said beam to a new location as said multiplicity of air pillows cooperate in absorbing shocks, ground irregularities and roadway conditions tending to set up torsional strains lengthwise of said beam.
